UNITED STATES PATENT OFFICE.

STANLEY JOSEPHUS SHEPARD, OF PORTERVILLE, CALIFORNIA.

FASTENING MEANS FOR HAMMERS AND THE LIKE.

Application filed November 30, 1925. Serial No. 72,321.

My invention relates to hammers, axes and similar tools, and it is a purpose of my invention to provide simple, inexpensive and durable fastening means applicable to any tool head or blade and any tapered tool handle for permanently securing the head on the handle, the fastening means being adjustable to accommodate itself to handles of different taper and to permit retightening of the head on the handle in event of loosening due to enlargement of the tool head stock or contraction of the handle, either of which may occur after long use.

I will describe only one form of fastening means for hammers and the like embodying my invention, and will then point out the novel features thereof in claim.

In the accompanying drawings:

Figure 1 is a view showing in side elevation, and partly in section, one form of fastening means embodying my invention in applied position with respect to a hammer;

Figure 2 is a horizontal sectional view taken on the line 2—2 of Figure 1;

Figure 3 is a vertical sectional view taken on the line 3—3 of Figure 1;

Figure 4 is an enlarged sectional perspective view of the hammer head shown in the preceding views.

Referring specifically to the drawings, in which similar reference characters refer to similar parts in each of the views, my invention in its present embodiment is shown applied to a hammer, although it is to be understood that the fastening means is applicable to any form of tool comprising a handle having a tapered portion and a tool head provided with a tapered socket in which the tapered portion of the handle is received. The hammer here shown comprises a handle 15 having an end portion 16 tapered toward its free end and adapted to be inserted into the tapered socket 17 of a hammer head 18, it being understood that the taper of the socket is slightly less than the taper of the handle so that the handle can be inserted only part way through the socket.

The fastening means embodying my invention comprises a pair of racked elements 19 in the form of rectangular plates provided on their outer faces with transversely disposed teeth, all of which extend in the same direction and toward the handle 15 when in applied position thereto. These racked elements 19 are snugly fitted in recesses 20 formed in the tapered portion 16 of the handle and at op-

posite sides thereof. The teeth of the elements are substantially flush with the surface of the tapered portion in order that such portion can be readily inserted into the socket 17 of the hammer head.

The fastening means further includes a pair of pawls 21 formed of spring steel and having their lower ends, as when viewed in Figure 3, secured by means of rivets 22 in pockets or recesses 23 formed at opposite points on the wall of the socket 17. The pawls, as well as the pockets are preferably tapered transversely, and the free ends of the pawls are curved outwardly to provide teeth 24 which, under the inherent resiliency of the metal of which they are formed, project from the pockets into the socket for engagement with the teeth of the racked elements 19.

In applying the handle to the hammer head 75 the tapered portion 16 is readily insertable into the socket 17, and during this operation the toothed ends 24 of the pawls 21 are forced inwardly in the pockets 23 until the racked elements 19 reach the pawls, when the latter 80 spring inwardly into engagement with the elements. By virtue of the direction in which the teeth of the racked elements extend, it will be manifest that the tapered portion can be inserted into the socket until it has tight engagement therewith, the pawls 21 in the meantime sliding over the toothed surface of the racked elements. With the tapered portion 85 in final position within the socket the teeth 24 of the pawls 21 engage certain teeth of the racked elements 19, as illustrated to advantage in Figure 3, and in such manner that the hammer head is securely locked on the tapered portion of the handle against outward movement on the tapered portion. Any tendency 90 of the head to fly off of the handle during use of the tool is effectively resisted by the pawls engaging the racked elements, but should the hammer head work loose after extended use because of shrinking or contraction of the tapered portion, it will be clear that the tapered portion can be further inserted into the socket to render a tight connection between the two, and in the final position the pawls still 95 engage the racked elements to securely lock the head in the new position.

Although I have herein shown and described only one form of fastening means for hammers and the like embodying my invention, it is to be understood that various 100 changes and modifications may be made therein without departing from the spirit of the 105

invention and the spirit and scope of the appended claim.

I claim:

5 A tool comprising a head having a tapered socket formed with recesses, spring pawls secured in the recesses and having their toothed ends normally projecting from the recesses, a handle having a tapered portion insertable

into the tapered socket and provided with recesses, and racked elements in the recesses of the tapered portion of the handle operating to permit insertion of the tapered portion of the handle into the socket but to engage the pawls and thus lock the handle against withdrawal from the socket.

STANLEY JOSEPHUS SHEPARD.
